UNITED STATES PATENT OFFICE.

JOSEPH SACHS, OF NEW YORK, N. Y.

DESIGN FOR AN AUXILIARY FIRE-ALARM BOX.

SPECIFICATION forming part of Design No. 22,090, dated December 27, 1892.

Application filed August 5, 1892. Serial No. 442,281. Term of patent 14 years.

To all whom it may concern:

Be it known that I, JOSEPH SACHS, a citizen of the United States, residing at New York, in the county of New York, in the State of New York, have invented and produced a new and original Design for Auxiliary Fire-Alarm Boxes, of which the following is a specification, reference being made to the accompanying drawings, forming a part thereof.

10 Figure 1. is a top view of the box and Fig. 2. a side view of the same.

15 My new and original design consists of a flat rectangular base C; the cylindrical posts or pillars d; the side and end panels D; the top panel A; and the frame B surrounding said top panel. Within the corners of the frame B are the representations of screw heads |

a. The posts or pillars d extend up from the base C a short distance from the corners thereof as shown. The said posts or pillars and the bottom edge of the frame B, extend out from the panels D, so as to give the latter the appearance of being recessed within said posts or pillars and said frame B. The top panel A is recessed within the frame B and the inner edges thereof are beveled as shown.

20 Having now described my original design, I claim—

25 The design for auxiliary fire alarm box, as herein described and shown.

JOSEPH SACHS.
